GARBAGE CAN SUPPORT

Sam Brustein, Akron, Ohio

Application March 3, 1950, Serial No. 147,489

4 Claims. (Cl. 248—147)

1

This invention relates to supporting stands for rubbish and garbage cans.

While stands for this purpose have been provided in the past they have been generally found undesirable for a number of reasons, such as that they were required to be made of a plurality of separate parts welded or otherwise secured together. In addition to being uneconomical to manufacture, such devices were easily damaged. The prior art devices, in general, have been so constructed that removal and replacement of garbage cans has been rather difficult.

It is one object of the present invention to provide an improved garbage can supporter which may be economically manufactured with a minimum of parts.

Another object of the invention is to provide a garbage can support of the character described having improved means for shiftably mounting the usual closure member or lid in association with the top of the can, in a manner which does not interfere with said removal or replacement of the can with respect to the support.

A further object of the invention is to provide a garbage can support which may be compactly stacked in nesting relation with a plurality of like supports or nested for shipping or storage purposes.

A further object of this invention is to provide a garbage can support, wherein the containers are easily removed and replaced with a minimum of lifting.

The foregoing and other objects of the invention will be manifest from the following brief description and the accompanying drawings.

Of the drawings:

Figure 1 is a perspective view illustrating improved garbage can supporting device in accordance with the invention, with typical garbage can supported therein.

Figure 2 is a perspective view, similar to Figure 1, but with the garbage can and closure member removed.

Figure 3 is a side elevation of the supporting device with a garbage can supported therein, the device being shown anchored in the ground as in use.

Figure 4 is a side elevation illustrating the manner of nesting a number of said supporting devices, as for shipping or storage purposes.

Figure 5 is a perspective view showing the supporting device of Figures 1, 2 and 3, but in a flat condition, in which it may be initially formed prior to bending as best shown in Figure 2.

Referring particularly to Figures 1 and 2, there

is shown a garbage can 10 of known type mounted on a supporting device 11 embodying the features of the invention, the can having fitted over the top thereof the usual flanged lid 12, to the central portion of which is attached an upwardly arched handle 13.

As best shown in Figure 2, the support 11 includes a main frame part 15 formed from a single length of heavy wire, opposite end portions thereof constituting laterally spaced, front uprights 16 and 17, with the central portion of the wire reversely bent to provide a third upright 18, rearwardly of said front uprights, composed of two closely adjacent, co-extending portions 19 and 20, and intervening portions 21 and 22 between the upper ends of said portions 19 and 20 and the upper ends of the front uprights 16 and 17, respectively, together forming a U-shaped top rail 21a slightly wider than the upper portion of the can. Each upright has formed adjacent the lower end of the same a reversely bent loop 25 providing horizontal projections 26, 27 and 28, 29, which act as stops to limit the depth to which the lower ends of the uprights may be projected into the earth or ground P, as shown in Figure 3.

At points well above said stop projections the rear upright 18 is reversely bent in a vertical plane to provide a double eyelet 29 which is closed about the central portion of a U-shaped member 30 of heavy wire, the outer ends of which are received through oppositely inwardly projecting, closed eyelets 31 and 32 similarly formed in the front uprights, the member 30 being locked in place by having the ends thereof bent into eyelets 33 and 34. Thus, the U-member 30 reinforces the projections 29, 31 and 32 as a supporting platform for a garbage can 10 (see Figures 1 and 3), to be well above the ground level.

A holder 40 is provided for attaching the cover 12 to the top of the support 11 to be swingable from and toward the closed positions thereof on the can 10. Accordingly, as best shown in Figures 1 and 2, the holder comprises a short length 41 of heavy wire formed adjacent the central portion of the same to have two eyelets 42 and 43 which are closed about the top rail portions 21 and 22, at opposite sides of rear upright 18, the portion 43a intermediate these eyelets being bent in loop-form at 43b, in a plane substantially at right angles to normally upwardly extending, substantially spaced, parallel portions 44 and 45. The loop 43b provides a stop element engageable with the rear upright to limit upward swinging movement of holder 40. The free end portions 43 and 43 of said length

of wire 41 are bent to extend forwardly of the vertical portions 44 and 45, and the extreme end portions 50 and 51 are bent laterally oppositely outwardly, whereby said forwardly extending portions are compressible inwardly, against the inherent resiliency of the material of the holder, to be received through the handle 13 of the lid. When the end portions 50 and 51 are released, they will yieldingly engage opposite sides of the handle, as best shown in Figure 1, in which position the lid will be retained on the holder by the laterally extending ends 50 and 51. The arrangement is such that the holder, with the lid thereon is swingable on the rear portions of the rail parts 21 and 22, from the position thereof shown in Figure 1 to a position rearwardly of the frame 11, in which the lid will be supported out of the way of the top of can 10 by stop engagement of the looped part 43 of the holder with the rear upright 18.

In use of the improved garbage can support 11, it is first anchored in upright position by pressing the ends of the three uprights 16, 17 and 18 into the ground G until the stop projections 26, 27 and 28, 29 engage the ground, in which condition the can-supporting platform 30 will be elevated substantially above the ground to be out of reach of rodents and other animals, as well as out of water or moisture on the ground which would cause a can on the support to be more susceptible to rusting. The can 10 is easily mounted on the platform 30 or removed therefrom, for emptying or cleaning purposes, through the open space between the front uprights 16 and 17 and with a minimum of lifting of the can, while the lid is supported on holder 40 in the previously described rearward stop position. When the lid is properly positioned on the can the latter cannot readily be removed or knocked from the support, due to the lid being attached to the holder 40.

Because of the U-shape of part 30, the support 11 is open at the front along the entire length thereof and to a substantial extent inwardly of the same, and any number of similarly shaped or formed supports 11 may be nested one within the other substantially in the manner shown in Figure 4. This feature is highly advantageous from a standpoint of economy of space, as for storing substantial numbers of the supports, as well as economy in packaging and shipping the same.

The improved support is also economical from a manufacturing standpoint, as, for example, because the main frame part 11 may be formed substantially complete in the flat condition shown in Figure 5, with a minimum of relatively simple bending operations, as in an automatic machine, after which the top rail parts 21 and 22 are bent to the aforementioned arcuate shape of Figures 1 and 2, and the U-shaped can-supporting member 30 is fixed in place (see Figures 2 and 3). The lid holder 40 may be attached to the frame 11 either before or after the frame is fully formed.

Thus, has been provided a garbage can support which is very economical for manufacturing, storage and shipping purposes, and which is convenient and easy to use as described.

Modifications of the invention may be resorted to without departing from the spirit of the invention or the scope of the appended claims.

What is claimed is:

1. A garbage can or like support comprising a frame formed of relatively stiff, elongated material, upward extensions from free bottom ends

of the frame material constituting laterally spaced front uprights, said front uprights being bent rearwardly therefrom at the top of the frame to provide laterally opposite can-retaining side rails, continuations of said opposite side rails extending downwardly at the rear of the frame and terminating at the bottom thereof to provide a rear supporting upright coextensive with said front uprights, means retaining together said downwardly bent continuations constituting said rear upright, said front and rear uprights having ground-engaging portions at the bottom of the frame and having looped portions formed therein to extend inwardly of the frame at a level intermediate said opposite side rails and said ground-engaging portions, said looped portions providing support for a said can received between said opposite rails, and a separate restraining member interconnecting said looped portions, at least the portion of said frame above said looped portions being open at the front between said front uprights unobstructedly to receive a garbage can from and toward said support thereof on said looped portions.

2. A garbage can or like support comprising a frame formed of relatively stiff, elongated material, upward extensions from free bottom ends of the frame material constituting laterally spaced front uprights, said front uprights being bent rearwardly at the top of the frame to provide opposite can-retaining side rails converging to a point of adjacency at the rear of the frame, downwardly bent continuations of said opposite side rails from said point of adjacency terminating at the bottom of the frame, means retaining together said downwardly extending continuations to constitute a rear supporting upright, said front and rear uprights having off-set portions bent therein to provide stop shoulders at a level engageable with a ground surface when the bottom ends of the uprights are inserted in the ground, said uprights having looped portions formed therein to extend inwardly of the frame at a level intermediate said opposite side rails and said off-set portions and providing support for a said can received between said opposite rails, and a separate restraining member interconnecting said looped portions to hold said front and rear uprights in peripherally spaced relation, at least the portion of said frame above said looped portions being open at the front between said front uprights unobstructedly to receive a garbage can from and toward said support thereof on said looped portions.

3. A garbage can or like support comprising a frame formed of relatively stiff, elongated material, upward extensions from free bottom ends of the frame material constituting laterally spaced front uprights, said front uprights being bent rearwardly at the top of the frame to provide opposite can-retaining side rails converging to a point of adjacency at the rear of the frame, downwardly bent continuations of said opposite side rails from said point of adjacency terminating at the bottom of the frame, means retaining together said downwardly bent continuations to constitute a rear supporting upright, said front and rear uprights having off-set portions bent therein to provide stop shoulders at a level engageable with a ground surface when the bottom ends of the uprights are inserted in the ground, said uprights having looped portions formed therein to extend inwardly of the frame at a level intermediate said opposite side

rails and said off-set portions and providing support for a said can received between said opposite rails, and a separate restraining member interconnecting said looped portions to hold said front and rear uprights in peripherally spaced relation, at least the portion of said frame above said looped portions being open at the front between said front uprights unobstructedly to receive a garbage can from and toward said support thereof on said looped portions, a holder having spaced apertured portions receiving said side rails at opposite sides of said rear uprights to be forwardly and rearwardly swingable thereon and having a forward extension provided with means for releasable attachment to the usual handle on the lid of a garbage can, whereby the lid is swingable from and toward closed position on the can supported in the frame.

4. A garbage can or like support comprising a frame formed of relatively stiff, elongated material, upward extensions from free bottom ends of the frame material constituting laterally spaced front uprights, said front uprights being bent rearwardly at the top of the frame to provide opposite can-retaining side rails converging to a point of adjacency at the rear of the frame, downwardly bent continuations of said opposite side rails from said point of adjacency terminating at the bottom of the frame, means retaining together said downwardly bent continuations to constitute a rear supporting upright, said front and rear uprights having offset portions bent therein to provide stop shoulders at a level engageable with a ground surface when the bottom ends of the uprights are inserted in the ground, said uprights having looped portions formed therein to extend inwardly of the frame at a level intermediate said opposite side rails and said off-set portions and providing support for a said can received be-

tween said opposite rails, and a separate restraining member interconnecting said looped portions to hold said front and rear uprights in peripherally spaced relation, at least the portion of said frame above said looped portions being open at the front between said front uprights unobstructedly to receive a garbage can from and toward said support thereof on said looped portions, a holder being pivotally mounted at the top rear of said frame to be releasably attached to the lid of a garbage can whereby the same is swingable from and toward closed position on the can supported in the frame, said holder comprising a separate length of relatively stiff wire formed at the central portion thereof to have laterally spaced eyelets receiving said opposite rails at points adjacent opposite sides of said rear upright to be swingable forwardly and rearwardly of the frame, the portion of said length intermediate said eyelets being looped to provide a stop element engageable with said rear upright in a rearwardly swung lid-raised position of the holder, the end portions of said length extending forwardly to be engageable through an arched handle on a said can lid by compressing the end portions together against the inherent resiliency of the wire, the extreme ends of said end portions being oppositely out-turned to retain the lid on the holder.
